(57) **CLAIM**

I claim the ornamental design for the dental carpule, as shown and described.

DESCRIPTION

FIG. 1 is a front perspective view of the dental carpule.

FIG. 2 is a rear perspective view of the dental carpule.

FIG. 3 is a top view of the dental carpule.

FIG. 4 is a bottom view of the dental carpule.

FIG. 5 is a left side view of the dental carpule.

FIG. 6 is a right side view of the dental carpule.

FIG. 7 is a back side view of the dental carpule; and,

FIG. 8 is a front side view of the dental carpule.

The broken line portions of the dental carpule are not claimed as part of the claimed design. The dot-dash lines show boundaries of the claimed design and are not claimed as part of the claimed design.
